UNITED STATES PATENT OFFICE.

THOMAS A. DELANEY AND EUGENE H. MALANY, OF SYRACUSE, NEW YORK.

COIN-CONTROLLED LOCK.

1,168,609.

Specification of Letters Patent.

Patented Jan. 18, 1916.

Application filed April 23, 1912. Serial No. 692,682.

To all whom it may concern:

Be it known that we, THOMAS A. DELANEY and EUGENE H. MALANY, of Syracuse, in the county of Onondaga, in the State of New York, have invented new and useful Improvements in Coin-Controlled Locks, of which the following, taken in connection with the accompanying drawings, is a full, clear, and exact description.

This invention relates to certain improvements in coin controlled locks for lockers adapted to be installed in any place or places frequented by numerous individuals, such as school-houses, club rooms, ball rooms, dining rooms, barber shops and other more or less public places for receiving coats, hats, umbrellas and other articles or wearing apparel. These lockers are preferably made in the form of cabinets of sufficient size to receive one or more of the articles previously mentioned and may be installed as individual or connected units along the wall or in rows in any available space within the room or building provided therefor, each unit being provided with a normally locked door and a coin slot positioned together with suitable coin controlled manually operated mechanisms for unlocking the door and wholly or partially closing the coin slot to prevent the passage of a coin therethrough when the articles are locked therein by the closing of the door.

The main object, therefore, is to prevent inadvertent or malicious removal of such articles by any other than the owner.

Another object is to provide for the automatic delivery of a suitable identification check to the patron of each particular locker or compartment and to equip each locker with suitable means preferably electrical, controlled by an attendant other than the patron for unlocking any particular locker upon the receipt of the check corresponding to such compartment previously delivered by the machine to the patron.

Another object is to provide for the simultaneous restoration of the door-releasing, slot closing and check delivery mechanisms to their normal positions when the door is unlocked by the attendant.

Other objects and uses relating to specific parts of the apparatus will be brought out in the following description:

In the drawings—Figure 1 is a perspective view of a cabinet embodying a series of, in this instance three, lockers showing diametri-

cally an electric circuit including therein a corresponding number of circuit closers adapted to be operated by the attendant for controlling the opening of the doors upon the presentation of the identifying checks.

Fig. 2 is an enlarged horizontal sectional view through one of the end lockers and portion of the next adjacent locker taken on line 2—2, Fig. 1. Fig. 3 is a still further enlarged horizontal vertical sectional view through a portion of one side of one of the lockers taken on line 3—3, Fig. 2 showing more particularly the guide slot and chute together with the mechanism for operating the door lock and slot closure and discharging the checks from the delivery tube. Fig. 4 is a side elevation partly in section of the mechanism shown in Fig. 3 except that the sliding member operated by the plunger through the medium of the coin lock is locked in operative position for locking the door, closing the slot and registering the check receiving opening in the slide with the check delivery chute. Fig. 5 is a horizontal sectional view taken on line 5—5, Fig. 3 except that the plunger and sliding plate connected thereto are shown in top plan. Fig. 6 is a detail horizontal sectional view taken on line 6—6, Fig. 3 showing more particularly the door lock and its operating means. Fig. 7 is a detail horizontal sectional view taken on line 7—7, Fig. 3 showing the means for operating the closure for the slot. Fig. 8 is a transverse vertical sectional view taken on line 8—8, Fig. 3 showing the door lock and its operating means in elevation. Fig. 9 is a transverse vertical sectional view taken on line 9—9, Fig. 3 showing the slot closure and its operating means. Fig. 10 is a transverse vertical sectional view taken on line 10—10, Fig. 3 through the coin chute and plunger similar to the sliding plate and also showing the base plate and coin opening therethrough at the underside of the sliding plate. Fig. 11 is a detail sectional view of a portion of

the locker case and door showing the spring for opening the door.

In order that the operation and utility of our invention may be clearly understood, we have shown an upright cabinet —1—

having one or more, in this instance three, compartments —2— for receiving wearing apparel and other articles, each compartment being provided with a door —3— and a suitable housing —4—, the latter serving as a suitable inclosure preferably at one side

of the compartment for receiving the local parts of the mechanism employed to control the operation of the door, slot closure and check delivery. These mechanisms are the same for each compartment or locker and it will therefore be necessary to describe but one of them. Each of the doors —3— is closed and locked against the action of a suitable spring —5— which serves to spring the door open when unlocked, the inner side of each housing —4— being preferably hinged at its rear edge at —6— to permit access to the interior mechanisms for inspection or repairs when necessary and also for refilling the check chute and removing the coins and is locked in its closed position by a separate lock —7— to prevent interference with said mechanisms, checks, or coins. The keeper as —8— for each of the doors —3— preferably extends and is deflected inwardly a sufficient distance beyond the door to automatically spring the lock when the door is closed. Each of the housings —4— forms a chamber —9— which is relatively shallow transversely as compared with its adjoining compartment —2— for receiving the mechanisms previously referred to, the lower portion thereof serving as a container to receive and conceal any coins which may be inserted through the coin slot of the corresponding locker from which they may be removed by opening the side —4— of the chamber —9—. Each locker is provided with an exposed coin inlet or slot —10—, a plunger —11—, and a check outlet —12— opening into a delivery pocket —13—, these parts being arranged one above the other preferably in the front side of the corresponding chambers —9— and therefore just at one side of the adjacent door —3—.

The coin inlet or slot —10— communicates with a coin chute —14— secured to and extending inwardly from the front portion of the housing —4— with sufficient clearance between the front end thereof and the wall in which the slot —10— is located to permit the free transverse movement of a closure —15— which is employed to open and close the slot —10—. As shown more clearly in Fig. 9, this closure —15— is also provided with a lengthwise slot —16— normally registering with the slot —10— and of sufficient size to permit a coin as a nickel to pass therethrough into the chute —14—.

The inner lower side of the coin chute —14— is preferably open to permit the coin to gravitate into an underlying supplemental guide —17— which is mounted upon a forwardly and rearwardly sliding plate or bar —18— but is normally registered with the open lower side of the chute —14— as shown in Fig. 3, said plate —18— being provided with an opening —19— therethrough registering with the coin guide —17— to permit the coin to pass there-

through under certain conditions hereinafter described.

The sliding plate —18— is guided in its forward and rearward movement upon an underlying supporting plate or bed —20— forming a part of the housing —4—, said plate being also provided with an opening —21— therethrough registering with the overlying opening —19— in the supplemental coin guide —17— to allow the coin to gravitate therethrough into an underlying coin receptacle or drawer —23— in the chamber —9— so as to permit the removal of the coins when desired. The sliding plate —18— is provided with an upwardly projecting boss —24— preferably at the rear of the coin guide —17— for receiving a forwardly projecting stem or spindle —25— along and upon which the plunger —11— is movable.

As shown in Fig. 3, this plunger is tubular and fits with an easy sliding fit upon the outer end of the stem —25—, the inner end of said plunger constituting an abutment between which and the rear side of the coin guide —17— the coin as a nickel —a— is adapted to gravitate as it passes through the chute —14— and into the coin guide —17—.

The front portion of the sliding plate —18— upon which the coin guide —17— is mounted is spaced apart some distance above the stationary guide supporting plate —20— for receiving a pair of toggle levers —26— shown more clearly in Fig. 6. These toggle levers are pivoted to each other end to end, one of them being pivoted at —27— to the supporting plate —20— while the other one is pivoted at —28— to the short arm of a rocking lever —29—, the latter being also pivoted at —30— to the plate —20— for operating a door lock —31— shown more clearly in Figs. 3, 6, 8 and 10.

The joined ends of the toggle levers —26— are normally flexed forwardly to one side of a direct line between the pivots —27— and —28— across the slot —21— a distance from the inner end of the plunger —11— less than the diameter of the coin so as to temporarily support a coin after being inserted through the coin slot and chutes, thereby constituting a coin lock between the inner end of the plunger —11— and sliding frame —18—.

It therefore follows that when no coin is present between the inner end of the plunger and rear side of the coin guide —17—, said plunger is free to move back and forth to and from a normal starting position and is returned to such position by a retracting spring —32— shown more clearly in Fig. 3, said spring being located within the tubular portion of the plunger with one end bearing against the outer end of the stem —25— and its other end engaged with the closed outer end of the plunger. On the

other hand when a coin is present between the inner end of the plunger and rear side of the coin guide —17— it is evident that inward movement of said plunger will im- 5 part a similar movement to the sliding plate —18— through the medium of the coin lock —17—.

Secured to the underside of the sliding plate —18— are pendant lugs or shoulders 10 —33— and —34—, the shoulder —33— be- ing normally in close proximity to the front edge of the flexing joint of the toggle levers —26— so as to flex the joint to approxi- 15 mately the same angle to the opposite side of a direct line between the pivots —27— and —28— as the plate —18— is moved rearwardly by the plunger —11— while the other shoulder —34— is in position to en- 20 gage the rearwardly flexed joint of said toggle levers to return them to their normal positions upon the return of the sliding plate —18—. The object of this particular toggle action is to shift the locking mem- 25 ber —31— from its locking position to un- lock the door after the insertion of a coin and operation of the plunger —11—, the spring —5— serving to open the door im- 30 mediately upon its release, thus permitting the operator to place the desired articles within the compartment —2—.

After the articles have been placed in the compartment, the door is closed, causing the member —8— to engage and depress the locking member —31— against the action of 35 a retracting spring —35— which immedi- ately forces the lock into engagement with its keeper. Immediately after this rearward movement of the sliding plate —18— by means of the plunger —11— and coin lock —a— by which the toggle levers —26— are flexed to the rear side of a direct line be- 40 tween the pivots —27— and —28—, pres- sure upon the plunger —11— is relieved, thereby permitting said plunger to return 45 to its normal position to release the coin and allow it to gravitate through the opening —21— and into the underlying pocket —22—. This rearward movement of the sliding plate —18— is utilized to operate the 50 closure —15— for the coin slot —10— and also to deliver a check through the outlet —12— and into the exposed pocket —13— and for these purposes the closure —15— is provided with a hub —36— journaled 55 upon the tubular portion of the plunger —11— between the front wall as —37— and a partition —38— just at the rear of the front wall which serve to hold the hub against endwise movement on the plunger; 60 thereby keeping the closure —15— in close contact with the rear face of the front wall —37—.

The hub —36— is provided with a pend- 65 ant projection —39— riding in a cam or diagonal slot —40— on the front end of the

sliding plate —18— as shown more clearly in Fig. 7 so that when the plate —18— is moved rearwardly, the closure —15— will be rocked about the axis of the hub —36— to close it across the coin slot —10—, there- 70 by preventing the insertion of another coin until the plate is returned to its starting position.

A stationary check receiver or tubular reservoir —41— is supported upon the plate 75 —20— of the housing —4— in vertical aline- ment with a circular aperture —42— in the sliding plate —18— when the latter is in its normal position, the thickness of the plate being substantially equal to the thickness of 80 one of the checks so as to allow but one check to enter the aperture at a time, and it there- fore follows that when the sliding plate is moved rearwardly in the manner previously described, the lowermost check will be 85 shifted from beneath the tubular reservoir —41— and will be deposited through an opening —43— in the bed plate —20— di- 90 rectly into a delivery tube or chute —44— which is inclined downwardly and forwardly 95 and communicates with the outlet —12— and pocket —13—, thereby delivering the re- leased check to the exterior of the case and into the pocket —13—, the opening —43— and upper end of the chute —44— being dis- 100 posed at the rear of the upright receiver —41— or in line with the aperture —42— when the plate —18— is shifted to the limit of its rearward movement.

In order that the closure —15— may re- 105 main in its closed position across the coin slot —10— while the articles of the patron are locked in the compartment —2—, it is necessary to lock the sliding plate —18— against return movement and for this pur- 110 pose I have provided a pawl —46— pivoted at —47— to a portion of the main supporting frame or housing and adapted to engage with a notch or shoulder —48— on one edge of the sliding plate —18— as shown more 115 clearly in Figs. 4 and 5, said pawl being yieldingly forced to its locking position by means of a spring —50—. The pawl —46— is held in locking engagement with the sliding plate —18— by an armature —51— 120 of an electromagnet —52— shown more clearly in Figs. 3 and 4. This armature to- 125 gether with the electromagnet are mounted upon a portion of the main supporting frame or housing —4—, the armature being spring —51— pressed into locking engagement with the pawl by means of a spring —53—.

The electromagnets —52— are electrically connected in circuit with a corresponding number of circuit closers as push buttons —3'—, —3''—, and —3'''—, which may be located in proximity to or remote from the cabinet usually where most convenient for the attendant so that when the patron is ready to remove the articles previously de- 130

posited in a locker, the check which has also been previously delivered to him and bears a character identifying that particular locker, is taken to the attendant who then 5 presses the corresponding push button as —3'—thereby energizing the magnet —52— to draw the armature —51— out of locking engagement with the pawl —46—, thus permitting the sliding plate —18— to be returned by a retracting spring —56— shown more clearly in Fig. 4. This return of the sliding plate —18— operates the locking bolt —31— against its retracting spring to permit the door to be opened by the spring 10 —5— and at the same time the closure —15— is returned to its normal position with its slot —16— in registration with the coin slot —10—, the check opening —41— being also returned into registration with the lower end 15 of the check receiver —41— ready for a repetition of the operation after the patron has removed his articles from the locker and re-closed the dcor.

In operation assuming that the door which 20 is keyless is locked and that the sliding plate —18— and parts carried or operated thereby are in their normal positions and that a patron desires to place his garments or other articles within one of the lockers temporarily for safe keeping, he then inserts the required coin as a nickel through the registering slots —10— and —16— in the front wall —37— and slot closure —15— respectively and into the chute —14— from which 25 it gravitates into the underlying coin guide —17— at one side of the stem —25— of the sliding plate —18— so as to rest temporarily upon the flexing joint of the toggle levers —26— and against the inner end of the tubular plunger —32—. The patron then pushes the plunger —11— inwardly by hand, thereby transmitting similar inward sliding movement to the plate —18— through the medium of the coin lock —a— until the pawl 30 —46— is registered with and forced into interlocking engagement in the notch —48— by the spring —50— as shown in Fig. 4, thereby causing the forward shoulder or lug —33— to engage and flex the toggle levers —26— rearwardly from their normal positions to operate the lever —29— for withdrawing the locking bolt —31— for an instant sufficient to allow the door to be thrown open by the spring —5—, this unlocking of 35 the bolt taking place while the flexing joint of the toggle levers is in direct line between their pivots —27— and —28—.

The door being now open gives to the patron access to this particular locker only but simultaneously with the opening of the door, the closure —15— will have been moved across the coin slot —10— by means of the cam slot —40— on the front end of the sliding plate —18— and will remain in 40 this position until the sliding plate —18—

is released by the tripping of the pawl —46— in a manner presently described.

At about the same time that the door is opened and the coin slot covered by the closure —15—, the lowermost check will have been shifted by the plate —18— from the receiver —41— into the check chute —44— where it gravitates downwardly and forwardly into the pocket —13— at the front to be taken by the patron and kept until his 70 garments or other articles which have been previously placed in the locker are again wanted, it being understood that after the articles have been deposited in the locker, the door is closed and automatically locked. 75

Now when the patron desires the articles which have been placed in the locker, he takes his check to an attendant who has full control of unlccking any or all of the lockers, the check delivered having a number or other character corresponding to the number of the locker which has been thus appropriated. This attendant then selects and operates one of the push buttons or circuit closers —3'— corresponding to the number 80 of the locker designated by the check, thereby energizing the corresponding electromagnet —52— to draw the armature —51— out of holding engagement with the pawl —46—, thus permitting the sliding plate 85 —18— to be returned to its normal position by the retracting spring —56—. This return of the sliding plate —18— unlocks the dcor and allows it to be thrown open by the spring —5— and also shifts the closure 90 —15— to register its slot —16— with the coin slot —10— and at the same time the check opening —41'— in the plate —18— is brought into registration with the lower 95 end of the check receiver —41—, the parts 100 being now ready for repetition of the operations previously described, it being understood that the opening of the door enables the patron to remove the articles previously placed therein after which the door is closed 105 and automatically locked ready for repetition of the operation previously described.

What we claim is:

1. In combination with a cabinet having a door provided with a keeper, a coin-controlled lock supported by the cabinet separately from the door and comprising a pivoted locking member, a lever for withdrawing said locking member, a toggle connected to said lever for operating the same 115 to withdraw the locking member from the keeper, a hand-operated plunger, means for conducting a coin edgewise into the path of the plunger to be displaced thereby, and means actuated by the displacement of the 120 coin by the plunger for operating the toggle.

2. In combination with a cabinet having a door provided with a keeper, a coin-controlled lock mounted on the cabinet sepa- 125

rately from the door and provided with a locking member for engaging the keeper, a hand-operated plunger, a coin guide for conducting a coin edgewise into the path of the plunger to be displaced thereby, a sliding plate operated by the displaced coin and provided with an outlet passage therefor, means actuated by the plate for withdrawing the locking member from the keeper, and separate means also actuated by the plate when displaced by the coin for preventing the entrance of a coin to the guide.

3. A coin-controlled lock comprising a spring-projected locking bolt, a spring-retracted plunger operated by hand against the action of its retracting spring, means for conducting a coin edgewise into the path of the plunger to be displaced thereby when moved against the action of the retracting spring, a sliding plate actuated by the coin when displaced by the plunger and having a passage for the escape of the released coin therethrough, and means actuated by said plate for withdrawing the locking bolt and permitting it to return to its locking position while the coin and plate are still displaced by the plunger.

4. A coin-controlled lock comprising a spring-projected locking bolt, a spring-retracted plunger operated by hand against the action of its retracting spring, means for conducting a coin edgewise into the path of the plunger to be displaced thereby when moved against the action of the retracting spring, a sliding plate actuated by the coin when displaced by the plunger and having a coin passage therethrough, means actuated by said plate for withdrawing the locking bolt and permitting it to return to its locking position while the coin and plate are still displaced by the plunger, and separate means actuated by the plate for preventing the entrance of a coin to the conducting means.

45 5. In a spring-controlled lock, a spring-projected locking bolt, a hand-operated plunger, means for conducting a coin edgewise into the path of the plunger to be displaced thereby, a sliding plate actuated by the displaced coin and having a slot for the passage of the coin therethrough, means actuated by said plate for withdrawing the locking bolt and permitting it to return to its locking position while the coin and plate are still displaced by the plunger, an automatically operating detent for holding the plate in its displaced position independently of the plunger, and means actuated by said plate when displaced for preventing the entrance of a coin into the conducting means.

60 6. In a coin-controlled lock, a spring-projected locking bolt, a hand-operated plunger, means for conducting a coin edgewise into the path of the plunger to be displaced thereby, a sliding plate actuated by

the displaced coin and having a coin passage therethrough, means actuated by said plate for withdrawing the locking bolt and permitting it to return to its locking position while the coin and plate are still displaced by the plunger, an automatically operating detent for holding the plate in its displaced position independently of the plunger, means actuated by said plate when displaced for preventing the entrance of a coin into the conducting means, separate means for tripping the detent and plate, and a spring for returning the plate to its starting position.

7. In a coin-controlled lock, a spring-projected locking bolt, a spring-retracted plunger, means for conducting a coin edgewise into the path of the plunger to be displaced thereby when operated against the action of its retracting spring, a sliding plate actuated by the displaced coin and having a coin passage therethrough, means actuated by the plate for withdrawing the locking bolt, a delivery chute across which the sliding plate is movable, and means for conducting checks into the path of the sliding plate, said checks being displaced by said plate into the delivery chute.

8. In a coin-controlled lock, a spring-projected locking bolt, a spring-retracted hand-operated plunger, a coin guide for conducting a coin edgewise into the path of the plunger to be displaced thereby, a sliding plate actuated by the displaced coin and having a coin passage therethrough, means actuated by the plate for withdrawing the locking bolt and permitting it to return to its locking position while the coin and plate are still displaced by the plunger, means actuated by the sliding plate for preventing the entrance of a coin to the guide while the plate is displaced, a detent for holding the plate in its displaced position, means for tripping the detent, and a spring for retracting the plate when the detent is tripped.

9. In combination with a cabinet having a door provided with a keeper, a coin-controlled lock mounted on the cabinet separately from the door and comprising a locking member for engaging the keeper, a tubular hand-operated plunger, a sliding plate movable lengthwise of the plunger and provided with an abutment and a guide stem projecting into the tubular plunger, means for conducting a coin edgewise between the abutment and inner edge of the plunger for operating the sliding plate as the plunger is moved inwardly, and means actuated by the sliding plate for withdrawing the locking member from the keeper.

10. In a coin-controlled locking device, in combination with a keeper, a pivoted locking member normally spring-pressed into engagement with the keeper, a sliding plate having a coin slot therethrough, a movable

coin rest directly under the plate in register with said slot to temporarily hold the coin in the slot, means on the plate for operating the coin rest as the plate is moved inwardly, means actuated by the coin rest for withdrawing the locking member from the keeper, an abutment on the plate provided with a forwardly projecting guide stem, a tubular hand-operated plunger telescoping 10 with said stem, and means for conducting a coin between the abutment and inner end of

the plunger and in registration with the slot in the plate to be displaced by said plunger for operating the plate, and a retracting spring for said plate.

In witness whereof we have hereunto set our hands this 13th day of April 1912.
